CLAIM

We claim the ornamental design for a head mounted audio-visual display system with connection cable, as shown and described.

DESCRIPTION

FIG. 1 is a rear perspective view of a head mounted audio-visual display system with connection cable showing our design in a first configuration;

FIG. 2 is a right side view thereof;

FIG. 3 is a left side view thereof;

FIG. 4 is a top view thereof;

FIG. 5 is a bottom view thereof;

FIG. 6 is a rear view thereof;

FIG. 7 is a rear perspective view of a head mounted audio-visual display system with connection cable showing our design in a second configuration;

FIG. 8 is a right side view thereof;

FIG. 9 is a left side view thereof;

FIG. 10 is a top view thereof;

FIG. 11 is a bottom view thereof; and,

FIG. 12 is a rear view thereof.

The broken lines shown in the figures show portions of the head mounted audio-visual display system that form no part of the claimed design.
